UNITED STATES PATENT OFFICE.

HENRY W. NELSON, OF ASHBY, MINNESOTA.

COMBINED FOLDING TENT AND BED.

1,335,456.

Specification of Letters Patent. Patented Mar. 30, 1920.

Application filed December 15, 1917. Serial No. 207,318.

To all whom it may concern:

Be it known that I, HENRY W. NELSON, a citizen of the United States, residing at Ashby, in the county of Grant and State 5 of Minnesota, have invented certain new and useful Improvements in Combined Folding Tents and Beds; and I do hereby declare the following to be a full, clear, and exact description of the invention, such as will 10 enable others skilled in the art to which it appertains to make and use the same.

My invention relates to improvements in combined folding tents and beds of that character wherein the combined folding tent 15 and bed may be folded into a compact and small package and placed in a comparatively small space.

Another object of my invention is to improve the construction of combined folding tents and beds and to so construct the combined folding tent and bed as to permit the bed or tent to be used independently of one another or arranged so as to be used combined.

25 A further object of this invention is to provide a combined folding tent and bed of this character, which is so constructed as to permit the bed to be readily and quickly set up and the tent so attached thereto as 30 to be positioned over the bed so as to provide a combined folding tent and bed.

Another object of this invention is to provide a combined tent and folding bed of this character, which will be simple, practical and comparatively inexpensive in construction and one that can be manufactured 35 and sold at a low cost.

With these and other objects in view the invention consists in the novel combination 40 and arrangement of parts hereinafter more fully described and set forth in the claims hereto appended.

In the drawings

Figure 1 is a perspective view of the combined folding tent and bed constructed in accordance with this invention and illustrating the same in set up position.

Fig. 2 is a side elevation of the combined folding tent and bed.

50 Fig. 3 is an end elevation.

Fig. 4 is a sectional view taken on the line 4—4 of Fig. 2 and looking in the direction of the arrow.

Fig. 5 is a fragmentary side elevation.

55 Fig. 6 is a fragmentary detail perspective view.

Fig. 7 is a fragmentary detail perspective view illustrating the manner in which one side rail is adapted to be connected.

Fig. 8 is a fragmentary side elevation 60 partly in section illustrating the manner in which the end rails are connected to one pair of the end legs.

Fig. 9 is a fragmentary perspective view illustrating the manner in which the standards of the tent are connected.

Fig. 10 is a fragmentary perspective view of the folding bed.

Fig. 11 is a perspective view of the bearing for the ridge pole of the tent.

Fig. 12 is a fragmentary sectional view of the end rails.

Fig. 13 is a fragmentary perspective view illustrating the manner in which one end of the side rails is connected to one of the end 75 legs.

Fig. 14 is a perspective view of the folding tent when used independently of the bed.

Like numerals of reference designate corresponding parts in all the figures of the drawings.

In the drawings, the numeral 5 generally designates the bed structure which includes side rails 6 and 7. The side rail 6 85 includes a pair of sections having their inner ends hingedly connected as indicated at 8.

The side rail 7 also is sectional and includes a pair of members arranged in end to end relation and having their adjacent 90 ends hingedly connected.

An auxiliary side rail 13 is arranged on one side of the side rail 7 and is adapted to be forced into clamping engagement with the rail 7 for supporting a fabric covering 95 or mattress 16 for the bed.

An angled lever 12 is pivoted intermediate its ends to one section of the auxiliary side rail 13 as indicated at 11 and has its forward end pivoted to one section of 100 the side rail 7. A link 9 is pivoted to the other section of the side rail 7 as indicated at 10 and at its opposite end to the pivot element 11. When it is desired to separate the sections of the rail 13 from the sections of the side rail 7, the handle of the lever 12 is drawn upwardly. The pivot element 10 operates within an elongated slot 10' and thereby permits the upper and lower sections to freely separate upon actuating the 110 lever 12.

The auxiliary side rail 13 includes a pair

of sections arranged in end to end relation and having their adjacent ends hingedly connected as indicated at 14.

The outer end of each section of the side rail 13 is hingedly secured as at 15 to the outer end of each section of the side rail 7. A fabric covering 16 constituting the mattress or body of the bed, has one longitudinal edge secured as at 17 to the exterior of the sectional side rails 6. The free longitudinal edge of this covering 16 is adapted to be clamped between the opposing faces of the sectional auxiliary rail and side rails 13 and 7 respectively. Thus it will be apparent that the covering will be held taut by virtue of the lever being moved into clamping position and urging the sectional rails 13 and 7 into engagement with the free edge of the covering as illustrated in Fig. 10 of the drawings.

To support the bed in upright position, I provide end legs 18 and center supporting legs 19. The end legs 18 comprise a plurality of members arranged in pairs and each 25 pair pivotally secured intermediate its ends as at 20. Each pair comprises a short member 21 and a longer member 22. The upper ends of the short members 21 are pivotally connected by the links 23 while the lower ends of the longer members are pivotally connected by the links 24. The upper ends of the longer members 22 of one pair of legs are pivotally secured to the side rails 6 and 7 at one end thereof by the links 25, while the other end legs are adapted to be removably secured to the free ends of the side rails 6 and 7 respectively. The upper free ends of the longer legs 22 which are adapted to be removably secured to the side 30 rails 6 and 7 have secured thereto the U-shaped members 26 in which are adapted to be secured the hooks 27 carried by the free end of each of the side rails 6 and 7 respectively as illustrated in Fig. 13, thus it can be seen that one pair of the end legs may 35 be readily removed from the side rails when the device is to be folded.

The center supporting legs 19 comprise a plurality of members arranged in pairs pivotally connected as at 28. One member of each pair is pivotally secured at its lower end by the links 29 and the upper ends of the other pair and provided with a catch 30 which is adapted to engage a lug 31 for 40 removably connecting the upper ends together. The free upper ends of the other pair have secured thereon bearings 31' which are adapted to be pivotally secured as at 32 to the side rails 6 and 7. It will be readily 45 seen that by virtue of these legs and their connections with the side rails that when assembled the bed will be supported in an upright position and by virtue of the inclination of the hooks 27 and the connection 50 of the end supporting legs to the side rails,

that the side rail will be inclined downwardly and outwardly in opposite directions. A pair of end rails 33 comprise sections 34 and 35, each section having its inner end reduced as at 36 on which reduced end is fitted a band 37. The band 37 is adapted to secure the sections 34 and 35 together by screws 38 which extend through the band and engage the reduced ends 36 thereof as illustrated in Fig. 12. The outer end of each section 34 and 35 of the end rails 33 have secured thereon and extending laterally from the ends thereof, a strip 39, which strip is adapted to be removably bolted to the upper end of the longer member 22 of each of the end supporting legs adjacent the upper end thereof as at 40 and clearly shown in Fig. 8 of the drawings.

It is to be understood that the opposite ends of the fabric covering 16 are to be provided with suitable pockets in which the sections 34 and 35 of the end rails are adapted to be so fitted as to hold the fabric taut when the bed is in a set up position, it being only necessary to unbolt the end rails from the legs when it is desired to collapse the bed.

A brace 41 has one end pivotally secured as at 42 to the exterior of the side rails 6 intermediate the ends thereof and its free end is pivotally secured as at 43' to one of the members of the center supporting legs on the exterior thereof, this brace acting to rigidly support the bed in a set up position.

The upper free end of each of the longer members 22 is provided with a bearing 43 which extends upwardly beyond the ends thereof. A standard 44 is removably secured at its lower end to each bearing 43 and is adapted to rest upon the upper side of the sectional side rails 6 and auxiliary rail 13. The standards 44 rise vertically from their removable connections with the bearings 43 and have hingedly connected to their upper ends as at 45 the struts 46. The lower ends of the standards are removably secured to the bearings 43 by bolts 47, which bolts permit the standards to be entirely removed from the bed structure when it is desired.

A T-shaped bearing 48 is pivotally secured to the free ends of the struts 46 as at 49 and the stem of the bearing is pivotally secured as at 50 to the outer end of each section 51 of the ridge pole. The inner ends of the sectional ridge pole are hingedly connected together as at 52 and are provided on their opposite sides from the hinge with the blocks 53 which prevent lateral swinging movement of the ridge pole in one direction.

Struts 46 are hingedly connected as at 45 to the standards 44 through the medium of the block 54 which is carried by the hinge 45 and has at its upper end a band 55 which

slidably engages the lower ends of the struts 46. The lower ends of the struts 46 are provided with a band 56 which slidably engages the standards 44 thus permitting the struts to be adjusted vertically on the standards 44. When it is desired to increase the height of the tent, it is only necessary to urge the band 56 carried by the lower ends of the struts 46 above the hinge 45. 5 When it is desired to use the device as an ordinary wedge tent, it is only necessary to urge the band 56 carried by the struts 46 downwardly below the hinge 45 of the standards 44, thus the standards and struts are 10 parallel. To hold the struts and standards parallel, the block is provided with hooks 57 which have their free ends embedded in the struts 46 and this prevents any relative movement of the struts with relation to the 15 standards. 20

It will be understood from the foregoing description taken in connection with the accompanying drawings, that the combined folding tent may be easily and quickly set 25 up for use and that the bed may be quickly folded and the same used as a tent only, or it may be further all disconnected and folded and rolled in a compact package which would take up a comparatively small amount 30 of space.

Having thus described my invention, what I claim is:

1. A device of the class described includ-

ing side rails, one of said side rails comprising a pair of sections, an auxiliary side rail 35 arranged above the sectional side rail and including a pair of sections, a lever pivoted to one section of the auxiliary side rail and to one section of the sectional side rail, the other section of the sectional side rail being 40 provided with an elongated slot, a link provided at one end with a pivot pin slidably and pivotally mounted in said elongated slot, said link being pivoted at its opposite end to said lever and hinges connecting the 45 adjacent outer ends of said side and auxiliary sections.

2. A device of the class described including side rails, one of said side rails being sectional, an auxiliary side rail adapted for 50 clamping engagement with said sectional side rail and including a pair of hingedly connected sections, an angled lever pivoted intermediate its ends to one of the sections of the auxiliary side rail and having its forward end pivoted to one section of the sectional side rail, a link pivoted to the other section of the side rail and to the intermediate portion of said lever, and supporting 55 legs for said side rails.

In testimony whereof I affix my signature in presence of two witnesses.

HENRY W. NELSON.
